DRILL-GRINDING ATTACHMENT FOR ABRADING-WHEELS.

1,052,073.

Specification of Letters Patent.

Patented Feb. 4, 1913.

Application filed March 23, 1911. Serial No. 616,394.

To all whom it may concern:

Be it known that I, BONNIE L. MALLORY, a citizen of the United States, residing at Cleveland, in the county of Cuyahoga and State of Ohio, have invented a new and useful Improvement in Drill-Grinding Attachments for Abrading-Wheels, of which the following is a full, clear, and exact description, reference being had to the accompanying drawings.

This invention relates to drill-grinding attachments for emery wheels, the same having for its object, generally stated, the production of a device that is adapted to hold and guide the drill upon the convex or rounded surface of the emery wheel.

Further objects of this invention are the production of a device of the character stated in which the drill holding attachments are so mounted and operated as to produce the proper clearance at the rear of the cutting edges of the drill; in which the drill may be conveniently placed for grinding and be securely held in position; in which proper adjustments may be conveniently made for the sizes and lengths of drills, and in which the parts are so constructed as to be capable of convenient operation and economical manufacture.

One structure in which the above stated and other objects are attained is shown in the accompanying drawings, in which—

Figure 1 shows a portion of the wheel in side elevation with the grinding attachment applied thereto; Fig. 2 is a plan view of what is shown in Fig. 1, the upper parts of the holding rings for the grinding attachment being broken away; Fig. 3 is a view of the front of the attachment, or of the attachment as viewed from the emery wheel; Fig. 4 is a sectional view taken on the line 4—4 of Fig. 2, and Fig. 5 is a perspective view of parts of the grinding attachment, some of said parts being removed from their normal or assembled positions in order that they may be better illustrated.

Taking up a detailed description of the invention and employing the reference characters found on the drawings, 1 represents an abrading wheel, which may be made of emery or any other suitable material, said wheel being supported upon suitable frame pieces 2 that are secured on a support 3 of any desired character. Upon this same support, and in front of the convex edge of the

wheel, is the support for the grinding attachment, said support being shown as a socket member 4, although it may be of any other suitable character.

Extending within the socket member 4, and held therein by a set screw 5, is the stem 6 of the outer supporting ring 7 of the attachment. This ring is perfectly circular, and is provided with ring plates 8 and 9 that are secured to its sides and that project inwardly beyond the ring so as to form a channel for confining a pair of half rings 10 and 11, said latter rings being, in effect, a single ring that is divided for convenience in assembling only. The divided ring fits within the said channel with sufficient looseness to permit it to turn freely within the main ring 7. As appears from Fig. 3, the division line between the ring sections 10 and 11 is vertical and passes through the center of curvature of the main ring. At substantially their mid-points, the ring sections are provided with holes 12, in which are journaled the trunnioned ends 13 of a rocking cradle 14, the latter having a depending web 15 that preferably lies in the same vertical plane as the trunnions and has its lower edge curved concentrically with the main ring 7. This cradle also has what may be termed a trough portion 16, the same projecting beyond each side of the web and having its axis inclined with respect to the axis of the web at an angle of approximately sixty degrees. Within this trough is a V-block 17, the lower surface of which is preferably flat, while the upper surface is provided with a V-shaped groove. This block rests upon the upper end of one or more screws 18, by means of which the block may be raised or lowered in the trough, for a purpose hereinafter stated. For guiding the block within the trough, the walls of both are grooved, the grooves of the trough being shown at 19 and those in the block being shown at 20. When the parts are assembled, these grooves register and form vertical seats for guide pins 21, see Fig. 4, said pins being partly in the trough and partly in the block. At the front end of the trough 16 I secure a gage 22, the same projecting in the direction of the emery wheel, and then turning across the rounded face of the latter, said gage being for the purpose of correctly positioning the drill, the latter being laid in the channel of the V-block, as

indicated at 23. When thus positioned, the block is raised or lowered, depending upon the manner in which it is already set and the size of the drill to be ground, until the 5 gage engages one of the flutes of the drill, when the latter is in position for grinding. For forcing the drill against the emery wheel, I mount a set-screw 24 in an adjustable post 25 in such a manner that it may be 10 screwed against the end of the drill shank, the post being slidably mounted on an arm 26 that projects from the trough 16 and being held in its adjusted positions by a set screw 27.

15 As is shown in Fig. 2, the drill is presented to the wheel at an angle of about thirty degrees from the normal at the point of application. If the drill were simply turned on its own axis, it would be ground 20 to a point, but there would be no clearance provided at the rear of the cutting edges, such clearance being necessary to the cutting action of the drill. If, on the other hand, the drill were held against rotation 25 and were simply moved up and down by rocking the cradle 14, some clearance would be provided near the cutting edge, but the drill more remote from such edge would not be sufficiently ground. It therefore be- 30 comes necessary to give the drill both a rotary and a rocking movement in order to grind the same in the form of a spiral which recedes from the cutting edge, this being the best shape to grind the drill, since 35 it cuts its way into the metal in a spiral direction. In order to give the drill this double movement, I provide means for rotating or oscillating the cradle while it is being rocked on its trunnions 13. This 40 means consists of a guide 28 that extends across the lower part of the ring 7 at an angle of approximately twenty degrees, the same being secured, through its depending lugs 29, to bosses 30 on the stem 6 of the 45 attachment. The upper surface of the guide 28 is preferably curved, with the axis of the cradle as a center, and the web of the latter is provided with a notch 31 into which the guide extends.

50 As will be seen by reference to Fig. 1, the trunnions 13 are positioned slightly above the center of the wheel 1. When the cradle is in its normal position, as shown in said figure, the line of contact between the drill 55 and the wheel is substantially in the common plane of the trunnion and the wheel axis. For accurately adjusting the cradle, a lug 32 is provided on the guide 28, and a set screw 33 is projected through the lug 60 into position to engage the cradle and thus limit the downward movement of the drill at the cutting line. For holding the cradle in normal position, a spring 34 is coiled about the axis of the cradle, one end of the 65 same being attached to said axis and the

other end to the adjacent section of the divided ring.

While it is believed that the operation of the invention will be understood from the above description, it may be briefly stated 70 as follows: Assuming that the device is set for a three-quarter inch, and it is desired to grind a half inch drill, the latter is placed in the V-block, which is then lifted by the set screw 18 until the gage 22 rests against the drill and in the flute thereof. The post 25 is then adjusted until the screw 24 abuts against the end of the drill shank. By then bearing down on the post 25 or on the arm 26, the cradle is rocked on its trunnions 75 and the same is simultaneously turned in the bearing ring 7. This movement lifts the end of the drill that is against the wheel and, at the same time, twists the same, thereby causing the wheel to grind 80 the end of the drill in spiral shape. There are, of course, two cutting edges on the drill; and, after the above stated operation has been repeated until that side of the drill 85 is sufficiently ground, the latter is turned 90 over and the grinding is continued on the other side.

While the structure shown and described is very efficient, I realize that many of the details may be varied without departing 95 from the spirit of my invention, and I desire it to be understood that the following claims are not intended to be limited to such details any further than is rendered necessary by the specific terms therein em- 100 ployed.

Having thus described my invention what I claim as new and desire to secure by Letters Patent is—

1. In a device of the character described, 105 the combination with a supporting ring, of sliding members mounted within said ring, of a drill support within the ring and trun- nioned in the sliding members and means for sliding said members within the ring 110 when the drill support is rocked upon its trunnions.

2. In a device of the character described, 115 the combination with a supporting ring, of a second ring within the supporting ring and adapted for turning therein, a cradle trunnioned in said second ring, a drill sup- port carried by said cradle, and means for turning the second ring within the support- ing ring when the cradle is rocked upon its 120 trunnions.

3. In a device of the character described, 125 the combination with a main ring, of a sec- ond ring within the main ring and in the same plane therewith, said second ring be- ing adapted to turn within the main ring, pivoted means trunnioned within the second ring, a drill supporting device carried by the said pivoted means in position for hold- ing the drill at an angle to the plane of 130

the rings, and stationary means for engaging with the pivoted means and thereby turning the second ring within the main ring when the pivoted means is rocked on its trunnions.

4. In a device of the character described, the combination with a main ring, of a second ring within the main ring and in the same plane therewith, said second ring being adapted to slide within the main ring, a cradle extending across the second ring and trunnioned therein, a trough member on said cradle, a V-block within said trough member, said block being adapted to support a drill for grinding, means for raising or lowering the block within the trough member, and a guide stationarily mounted with respect to the cradle and engaging with the latter so as to turn it and the drill as the cradle is rocked upon its trunnions.

5. In a device of the character described, the combination with a main ring, of means for holding said ring stationary with respect to an abrading wheel, a second ring within the main ring and in the same plane therewith, said ring being adapted to turn within the main ring, a cradle extending across the second ring and trunnioned in the latter, a trough member on the cradle, a V-block in the trough member, means for guiding said block within said member, means for raising and lowering the block within the member so as to position the drill with respect to the abrading wheel, means for feeding the drill longitudinally against the wheel, an adjustable stop, spring means for normally holding the cradle against said stop, and a guide inclined to the axis of the cradle and engaging the latter so as to turn it and the second ring within the main ring when the cradle is rocked on its trunnions.

6. In a device of the character described, the combination with a main ring, means for holding said ring stationary in front of the convex surface of an abrading wheel, a second ring within the main ring and in the same plane therewith, said second ring being adapted to slide within the main ring, a cradle extending across the second ring and being trunnioned at its ends in said ring, a trough member on said cradle, said member having its axis at an angle to the axis of the cradle, a drill support within said trough member, means for adjusting said support for different diameters of drills, a gage finger on the trough member for engaging the drill when the said support is adjusted, and a guide stationarily mounted with respect to the cradle and engaging the latter for sliding the second ring within the main ring when the cradle is rocked on its trunnions.

7. In a device of the character described, the combination with a main ring, said ring being stationarily supported with respect to the convex surface of an abrading wheel, of

a second ring slidably mounted within the main ring and in the same plane therewith, retaining ring members secured to the main ring and projecting inwardly to hold the second ring in position, a cradle trunnioned in the second ring, an adjustable stop, a spring engaging the second ring and the cradle and being adapted to normally hold the cradle against said stop, a stationary guide extending at an angle to the axis of the cradle and engaging the latter so as to slide the second ring within the main ring when the cradle is rocked on its trunnions, and means carried by the cradle for supporting a drill, said means holding the drill at an angle to the said guide and to the axis of the cradle.

8. In a device of the character described, the combination with a main ring that is stationarily supported in front of the convex surface of an abrading wheel, of a second ring within the main ring and in the same plane therewith, the second ring being adapted to slide within the main ring, a cradle extending across the second ring and being trunnioned therein, said cradle having a trough member thereon, a V-block within the trough member, said block being adapted to support a drill for grinding, pin guides for said block, means for adjusting the block along the pins and within the said member, an arm on the said trough member, a post adjustably mounted on the said arm, a screw carried by said post and adapted to engage the shank end of the drill for forcing the latter against the abrading wheel, a gage finger carried by the trough member and adapted to engage the latter, said guide being inclined with respect to the axis of the cradle so as to cause the second ring to turn within the main ring when the cradle is rocked on its trunnion.

9. In a device of the character described, the combination with a main ring that is stationarily secured with respect to the convex surface of an abrading wheel, of a second ring within the main ring and in the same plane therewith, said second ring being adapted to slide within the main ring, devices secured to the main ring for retaining the second ring in position, a cradle extending across the second ring and being journaled therein, an adjustable stop, a spring engaging with the second ring and with the cradle for holding the latter against said stop, a guide stationarily mounted with respect to the cradle and engaging the latter, said guide being inclined with respect to the axis of the cradle so as to turn the second ring within the main ring when the cradle is rocked on its trunnions, a trough member on the cradle, said member extending at an angle to the guide and to the axis of the cradle, a V-block within the trough member, pin guides within the said member and within the block for guiding the latter, a screw

passing through the bottom of the trough and abutting against the V-block for adjusting the latter in the trough, an arm extending from the trough, a post adjustably mounted on said arm, a screw carried by the post in position for engagement with the shank end of the drill as it lies in the V-block, and a gage finger secured to the trough and extending into position for en-

gagement by the drill as the block is adjusted, as and for the purpose specified.

In testimony whereof, I hereunto affix my signature in the presence of two witnesses.

BONNIE L. MALLORY.
